UNITED STATES PATENT OFFICE.

EDWARD PENTONY, OF REDWOOD FALLS, MINNESOTA.

STOVE-LID LIFTER.

1,248,391.

Specification of Letters Patent. Patented Nov. 27, 1917.

Application filed April 7, 1916. Serial No. 89,645.

To all whom it may concern:

Be it known that I, EDWARD PENTONY, a citizen of the United States, residing at Redwood Falls, in the county of Redwood and 5 State of Minnesota, have invented new and useful Improvements in Stove-Lid Lifters, of which the following is a specification.

This invention relates to a device which may be employed to remove stove lids from 10 the stove particularly when said lids are in a heated condition.

The primary object of the invention is to provide a device of the class described having 15 handle members provided with pivotally connected and crossed offset portions, one of said portions terminating in a lifting foot to be received in the recess in a stove lid and arranged in advance of laterally extending tongues on the offset portion to bear 20 on said lid at one end of said opening and the other of said offset portions terminating in a jaw having an end to engage the stove lid adjacent the other end of the recess.

Another object of the invention is to provide 25 a device of the character described having a spring connected with one of the handle members and passing through a slot in the offset portion therein, and bearing against the other handle member to normally hold the end of said jaw and the lifting foot in spaced relation.

A still further object of the invention is 30 to provide a stove lid lifter of the class described in which one of the handle members has connected therewith a flexible element 35 having an end which may be removably connected with the other handle member to limit the opening movement of the handle members under the influence of the spring 40 associated therewith.

With these and other objects in view, the invention resides in the novel combination and arrangement of parts which will be hereinafter described and particularly 45 pointed out in the claim.

The preferred embodiment of the invention has been illustrated in the accompanying drawing, although no restriction is necessarily made to the precise details of construction therein shown, as changes, alterations, and modifications within the scope of 50 the claim may be resorted to when desired.

Like characters of reference denote corresponding parts throughout the several views 55 in the drawing, in which:

Figure 1 is a perspective view of a stove

lid lifter constructed in accordance with the invention.

Fig. 2 is a view in side elevation of a stove lid lifter showing the same engaged with a 60 stove lid.

Fig. 3 is a bottom plan view of the invention.

Referring now to the drawings in detail, the numeral 1 designates a handle member 65 having an enlarged and offset portion between its ends designated by the numeral 2, said offset portion having extending longitudinally thereof an elongated slot 3 intersected by a transversely extending opening 70 4 in said offset portion. The enlarged offset portion 2 of the handle member 1 terminates in an extension 5 which is curved and tapered to provide a jaw 6.

The handle member 1 is provided on its 75 underface for a portion of its length with a handle piece 7 which may be formed from wood, or other material which is a poor conductor of heat.

A second handle member 8 is provided 80 and has a reduced and offset portion 9 between its ends, said offset portion passing through the elongated slot 3 in the offset portion 2 of the handle member 1 and is pivotally connected therewith by a pivot pin 85 10 passing through said reduced and offset portion and through the opening 4 in the offset portion of the handle member 1. The reduced and offset portion 9 of the handle member 8 is slightly curved for a portion 90 of its length and terminates at one end in a widened portion providing an angularly extending lifting foot 11 in advance of 95 tongues 12 extending laterally from opposite sides of the slightly curved portion of the handle member 8, said tongues when the lifting foot has been inserted in the recess 14 in a stove lid 15, bear upon the lid adjacent an end of said recess. The handle member 8 has secured to its outer face, a handle 100 piece 16, similar to the handle piece 7 on the handle member 1, so that when the extension 11 on the handle member 8 is left within the recess 14 in the stove lid for a considerable length of time, the handle members will remain cool.

To normally hold the handle members 1 and 8 apart, a leaf spring 17 has one end secured to the handle piece 7 on the handle member 1, said spring being carried forwardly and upwardly through the slot 3, so that said spring for the greater portion of

its length contacts with the bottom face of the handle member 8, on which is a yoke 18 through which said spring is passed, with the yoke serving as a guide for the spring 5 as the handle members are moved toward each other.

The handle member 1 has formed at one end an eye 19 through which passes one end of a chain 20, said chain having secured to 10 its other end a snap hook 21 for engagement with a loop 22 on one end of the handle member 8, said chain being adapted to limit the opening movement of the handle members under the influence of the spring and 15 also provide a means by which the stove lid lifter may be suspended from a support.

When it is desired to remove a stove lid by means of the lifter, the lifting foot 11 is positioned within the recess 14 in the 20 stove lid, with the tongues 12 bearing upon the lid 13 adjacent one end of the recess 14. Pressure is now exerted upon the handle members 1 and 8 to cause the free end of the jaw 6 to contact with the top of the stove 25 lid adjacent the other end of the recess therein. With the parts in this position, the lid is firmly held upon the foot 11 by the jaw 6 without imposing undue strain upon the ears 12 of the lifter so that when 30 the lid is removed from the stove there is no opportunity for the lid to become disconnected from the lifter.

Copies of this patent may be obtained for five cents each, by addressing the "Commissioner of Patents, Washington, D. C."

To disengage the lifter from the lid, the pressure upon the handle members is released to allow the spring 17 to restore the 35 handle members to normal position at which time, the foot 11 may be withdrawn from the recess in the stove lid.

From the foregoing description, taken in connection with the accompanying drawing, 40 it is at once apparent that a stove lid lifter has been provided which is simple in construction, inexpensive of manufacture, and highly efficient in use.

Having thus described the invention, what 45 is claimed as new, is:

In a device of the class described, a handle member having a slot therein, a second handle member pivotally connected with the other handle member and passing through 50 the slot therein, a leaf spring having an end thereof secured to the outer face of the first mentioned handle member and passing through the slot therein to bear on the inner face of the second mentioned handle 55 member, and a yoke on the second mentioned handle member through which said spring is passed serving as a guide therefor.

In testimony whereof I affix my signature. 60
EDWARD PENTONY.

Signed in presence of—
